UNITED STATES PATENT OFFICE.

CHARLES S. S. GRIFFING, OF SALEM, OHIO.

IMPROVEMENT IN CARRIAGE-SPRINGS.

Specification forming part of Letters Patent No. 137,197, dated March 25, 1873.

To all whom it may concern:

Be it known that I, CHARLES S. S. GRIFFING, of Salem, in the county of Columbiana and State of Ohio, have invented a certain Improvement on Carriage-Springs, of which the following is a specification:

The nature of my invention consists in the employment, in combination with elliptic carriage-springs, of two or more guide-rods, arranged parallel to one another in vertical positions, in such a manner as to prevent all lateral movements of the spring in both vertical and horizontal directions, which distinguishes my improvement, broadly, from that class of elliptic carriage-springs provided with but one such guide-rod, which can only stop lateral motions in vertical planes. The guide-rods are also encircled by tubular rubber springs, performing their usual functions in conjunction with the elliptic spring.

Figure 1 is an elevation of my improved carriage-spring. Fig. 2 is a vertical transverse section thereof.

The same letters of reference are employed in both figures in the designation of identical parts.

The elliptic spring A is constructed in the usual manner, and fastened between the axle

and bolster of the vehicle. To the upper half of the spring are firmly secured two vertical parallel guide-rods, B B', by means of a plate, C, or other suitable device. The guide-rods stand upon the side of the spring, as best seen in Fig. 2, and their lower ends are placed in elongated bearings D D' suitably secured to the axle. These bearings are lined with Babbitt metal, or other non-frictional metal, to prevent the rapid wearing of the guide-rods, which must inevitably occur did the rods slide in iron sleeves. The rods should be placed about six inches apart, and each encircled by a tubular rubber spring, E, as shown.

What I claim as my invention, and desire to secure by Letters Patent, is—

An elliptic carriage-spring, A, in combination with the vertical guide-rods, two or more, B B'; elongated bearings D D', and rubber springs E, substantially as and for the purpose specified.

In testimony whereof I have signed my name to this specification in the presence of two subscribing witnesses.

C. S. S. GRIFFING.
